COMBINED HEEL SHELL AND COMB
FOR LOOMS

William A. Blanchard, Millbury, Mass., assignor
to Crompton & Knowles Loom Works, Worcester, Mass., a corporation of Massachusetts

Application June 6, 1950, Serial No. 166,424

10 Claims. (Cl. 139—77)

1

This invention relates to improvements in shedding mechanisms, such as the Knowles head, and it is the general object of the invention to provide a heel shell for the pivoted ends of vibrator levers combined with a comb to hold the levers in spaced relation.

The type of shedding mechanism to which the invention relates more particularly employs a series of vibrator levers pivoted on a heel pin and having mounted thereon vibrator gears pivotally connected to harness lever connectors. A pattern chain under the vibrator levers determines the vertical position of the gears with respect to two oppositely turning actuator cylinder gears. When the pattern chain lifts the lever it is necessary to provide some means for holding the pivoted end of the vibrator lever against upward motion relative to the heel pin, and this is customarily done by a heel shell parallel to the heel pin and extending over the pivoted or heel ends of the levers.

In order to insure correct spacing of the vibrator levers and registry thereof with the pattern chain it has also been customary in the past to employ a comb serving as a guide which permits vertical motion of the levers while holding them over their respective sections of the chain. In the past the comb has been held in fixed position on arms forming part of the frame of the shedding mechanism. This comb has been made separate from the heel shell and has required its own supporting means independently of the shell.

It is an important object of the present invention to make the heel shell and comb adjacent to the heel pin in a single unitary structure so that attaching means which serve to hold the shell in position will also hold the comb.

It is occasionally necessary to replace a broken or worn vibrator lever, in which event it has been common practice heretofore to remove the heel shell or swing it around the heel pin to permit upward movement of the heel and of the vibrator levers from the pin.

It is a further object of the invention to provide a combined heel shell and comb mounted to swing around the heel pin to a position in which the comb will be out of the path of the vibrator lever being removed.

It has also been customary to employ resiliently mounted chain guards which hold the pattern chains down against their cylinders and these have ordinarily had fixed mountings on the frame of the shedding mechanism.

It is another object of the invention to provide the combined shell and comb with a pattern chain guard mounted thereon and so disposed that the comb and guard can swing with the shell when

2

it is necessary to remove one of the vibrator levers from the shedding mechanism.

With these and other objects in view which will appear as the description proceeds, the invention resides in the combination and arrangement of parts hereinafter described and set forth.

In the accompanying drawings, wherein two forms of the invention are set forth,

Fig. 1 is a front elevation of a shedding mechanism, more particularly of the Knowles head type, having the preferred form of the invention applied thereto,

Fig. 2 is an enlarged vertical longitudinal section on line 2—2, Fig. 1.

Figs. 3, 4 and 5 are detailed vertical sections on lines 3—3, 4—4 and 5—5, respectively, of Fig. 2, parts being omitted,

Fig. 6 is a detailed plan view looking in the direction of arrow 6, Fig. 1.

Fig. 7 is a perspective view, parts broken away, of the combined heel shell and comb unit shown in Fig. 1.

Fig. 8 is a diagrammatic view indicating the manner in which the combined heel and comb unit is swung to a position permitting removal of a damaged vibrator lever,

Fig. 9 is a vertical section on line 9—9, Fig. 2, and

Fig. 10 is a view similar to Fig. 3, but showing the modified form of the invention.

Referring particularly to Fig. 1, the loom frame 1 has mounted thereon a shedding mechanism K provided with harness lever jacks 2 pivoted at 3 to the frame 4 of the shedding mechanism. Top and bottom rotary actuators 5 and 6, respectively, are driven in any approved manner in timed relation with the loom and are adapted for cooperation one at a time with vibrator gears 7 rotatable on vibrator levers. The mechanism K is adapted for use with shifting shuttle boxes and has vibrator levers H for the warp harnesses and levers B for the shuttle boxes (not shown). The frame 4 has front and back arms 9 and 10, respectively, which support a heel pin 11 on which the heel end of the vibrator levers, the left as viewed in Fig. 1, are pivoted. These levers have bearings 12 which open downwardly and are applied to the pin 11 by being fitted down over it from above.

The vibrator gear of each lever H is provided with a connector 13 for a harness jack lever 2. A pattern chain cylinder 14 supported for rotation carries a pattern chain 15 the bars 16 of which are fed progressively to a position under the vibrator levers H by the cylinder 14. Another chain not shown is provided for the levers B.

The right end of each vibrator lever as indi-

cated in Fig. 1 is adapted for cooperation with a lock knife 20 rocked periodically by a finger 21 which cooperates with a cam 22 rotating with the bottom cylinder 6. An inner comb 23 is mounted as at 24 on the frame 4 and spaces the inner ends of the vibrator levers. This comb has teeth which extend upwardly between the vibrator levers to hold them in vertical position.

It is customary to provide some form of guard for the pattern chain 15 to hold its bars down in proper position relative to the cylinder 14. One of these guards is shown in Fig. 1 and includes a stand 25 fixed to the forward arm 9 of the frame 4 and having a finger 26 pivoted thereto as at 27. A compression spring 28 surrounds a rod 29 having a nut 30 thereon which engages part of the finger 26. The normal effect of the spring 28 is to tend to turn the finger 26 in a clockwise direction as viewed in Fig. 1 down toward cylinder 14. Ordinarily, there is a second finger similar to finger 26 for the rear end of the chain bars 16 having a fixed mounting similar to the bracket 26. A second finger is provided herein but is mounted on the combined heel and comb unit and will be described hereinafter.

The matter thus far set forth is of usual construction and operates in the ordinary manner. When the pattern chain 15 permits a vibrator lever to be in low position the associated vibrator gear 1 will be given substantially a half turn by the bottom actuator 6 to rock the corresponding harness jack lever 2 in one direction, and when the jack lever is to be rocked in the opposite direction the pattern chain will lift the associated vibrator lever so that its vibrator gear can be turned in the opposite direction by the top rotary actuator 5. The vibrator levers turn angularly around the pin 11 when moving vertically under influence of the pattern chain.

In carrying the preferred form of the invention into effect a simple form of combined heel shell and comb unit U is provided. As shown in Fig. 7 the unit may be made of an inverted channel shaped member 35 having a top web 36 and inner and outer vertical flanges 37 and 38 shown at the right and left, respectively, in Fig. 7. Welded to the under side of the web 36 is a front bearing member 40 provided with a bore 41 to receive the front end of pin 11. The latter is secured as at 42 to the front and back arms 9 and 10 of the frame 4. A second bearing member 43 spaced rearwardly from the bearing 40 is also welded to the under side of the web 36 and has a bore 44 aligned with bore 41 to receive the pin 11.

Each of the levers H and B requires a form of guide comb which in the present instance is afforded by vertical slots cut in the inner flange 37 of the unit U. Thus, the forward part of this flange is provided with vertical slots 46 transverse of the member U and of such width as to accommodate the levers H. The rear part of flange 37 is provided with similar vertical slots 47 for the vibrator levers B.

Secured to the top web 36 are front and back lugs 50 and 51 respectively secured to the unit U preferably by welding. These lugs are secured to the arms 9 and 10 by screws 52 and 53 respectively which hold the unit U tightly to the frame 4 with the flange 37 in vertical position and the slots 46 and 47 correctly placed to effect registry of their corresponding vibrator levers with the pattern chain.

The heel 55 of each vibrator lever is provided

with a lug 56 concentric with the heel pin 11 and as shown in Fig. 4 these lugs 56 lie close to the under side of the web 36 of the unit U to prevent substantial upward movement of the outer ends of the vibrator levers when the latter are raised by the pattern chain. The flange 38 extends downwardly from the web 36 along the heels 55 of the several vibrator levers to give rigidity to the unit U. Except for the lugs 50 and 51 the unit is located between the arms 9 and 10, see Fig. 2.

Mention has already been made of the second chain guard finger which is shown more particularly in Fig. 6. This finger, indicated at 60, is pivoted as at 61 to a small stand 62 fastened as at 63 to that part of the flange 37 between the group of slots 46 and the group 47. A rod 64 surrounded by a compression spring 65 passes through part of the finger 60 and has a nut 66 on the lower end thereof. The action of finger 60 is similar to that of finger 26, and these fingers are alike except for the manner of their mounting. It will be apparent from Fig. 6 that the finger 60 and parts associated therewith are out of vertical alignment with the vibrator levers H and B, the groups of harness and shuttle box levers being separated by a space 67 to accommodate the guard finger 60 for angular movement around the pin 11.

When the preferred form of the invention is in normal position as shown in Figs. 1 and 2 the screws 52 and 53 will hold the unit U rigidly to the frame 4 and each lever will be properly guided by its slots 46 or 47. The finger 60 and associated parts will be in position to push down the rear end of any chain bar 16 which may tend to ride high as the cylinder 14 has its rotary chain feeding motion. The flange 37 serves as a comb to cause correct registry of levers H and B with the pattern chain.

Should it be necessary to replace a vibrator lever the screws 52 and 53 will be removed and the unit U will be swung around heel pin 11 from the full line position to the dotted line position shown in Fig. 8. During this swinging motion the finger 60 and stand 62 will move upwardly through the space 67 so that these parts need not be removed from the unit U. The flange 38 can engage the bottoms of the vibrator levers which serve as a stop to hold the unit U in the position shown in dotted lines in Fig. 8. After the damaged vibrator lever has been replaced the unit U and the finger 60 are swung back from the dotted line position to the normal full line position, Fig. 8, after which the screws 52 and 53 are replaced and operations can be resumed.

In order that the swinging motion of unit U and finger 60 may be free and unobstructed the arms 9 and 10 are provided with curved surfaces 70 over which the lugs 50 and 51 can move, see Fig. 9. These surfaces 70 are preferably concentric with the heel pin 11 and constitute a slight modification of the arms 9 and 10 as ordinarily found in the usual mechanism K.

It will be noted that when the unit U is in the dotted line position shown in Fig. 8 the comb flange 37 is spaced from the vibrator levers, but the latter will be held in vertical position by the usual comb 23, and when the unit is returned to its normal position the vibrator levers will require very little manipulation to effect registry with their guide slots 46 and 47.

In the modified form of the invention shown in Fig. 10 provision is made for holding the unit in fixed position without the lugs 50 and 51 or the

screws 52 and 53. In this form of the invention the unit, designated at U1, is similar to unit U, but has an intermediate bearing lug 75 formed with a split bearing 76 which can be clamped to the heel pin 11 by nut 77 on screw 78. Under ordinary conditions the nut 77 will clamp the bearing tightly against the pin and the unit U1 will be in normal position, but when it is desired to swing the unit to the dotted line position shown in Fig. 8 nut 77 is loosened to permit swinging of the unit U1 and is then again tightened after the unit has been returned to its normal position.

From the foregoing it will be seen that the invention sets forth a simple combined heel shell and comb unit for the vibrator levers of a shedding mechanism. While the invention has been set forth more particularly with respect to the well-known Knowles head, certain features of the invention are not necessarily limited to that type of mechanism. The unit U may be made of channel shaped steel and has a web 36 which limits upward movement of the lugs 56 of the vibrator levers and also has an integral flange 37 slotted as at 46 and 47 to provide a comb for the vibrator levers. In both forms of the invention the combined shell and comb is held rigidly in fixed position for normal operation, but when it is necessary to replace a damaged vibrator lever the fastening means, either the screws 52 and 53, or the nut 77, can be manipulated to permit swinging to the dotted line position of Fig. 8 to permit replacement of the damaged vibrator lever. It will also be seen that the guard finger 60 for the bars 16 of the pattern chain is mounted on the unit U or U1 and swings upwardly between the two groups of vibrator levers when the combined shell and comb is rocked about fixed pin 11.

Having thus described the invention it will be seen that changes and modifications of the foregoing specific disclosure may be made without departing from the spirit and scope of the invention.

What is claimed as new is:

1. In loom shedding mechanism having a frame including a heel pin, a plurality of vibrator levers having downwardly opening bearings pivoted on the heel pin, a combined heel shell and comb unit mounted on the pin for angular movement therearound and having a web extending over the levers normally restraining upward movement of the levers relative to the pin and having a comb depending from the web to space the levers, and means normally holding the unit stationary on the pin but releasable to permit swinging of the unit around the pin to a position enabling a lever to be lifted from engagement with said pin.

2. In loom shedding mechanism having a frame including a plurality of vibrator levers pivoted on a heel pin on the frame, a unit mounted for pivotal movement on the heel pin including a web extending over the levers to limit upward movement of the latter relative to the pin and including also a comb on the web in position to space the levers when the unit is in normal position, and holding means normally securing the unit in normal position but releasable to permit angular movement of the unit around the pin to a position in which a lever can be moved upwardly from the pin along a path at one side of said web and comb.

3. In loom shedding mechanism having a heel pin and a plurality of vibrator levers pivoted thereon, a combined heel shell and comb unit

5 mounted on and for pivotal movement around the pin, said unit having a web extending over the levers to limit upward movement of the latter with respect to the pin and having a comb flange depending from one side of the web formed with slots to receive and space the levers, a second flange depending from the other side of the web to reinforce the latter, and means normally holding the unit with the web thereof

10 over the levers and with the latter in said slots, said means being releasable to permit angular movement of the unit around the pin and the unit thereupon being turnable to lift the comb flange away from the levers and move the second flange into engagement with the levers enabling the latter to serve as a stop limiting angular motion of the unit around said pin.

15 4. In loom shedding mechanism having a frame supporting a heel pin on which a plurality of vibrator levers are pivoted, a combined heel shell and comb unit mounted on the pin for angular movement therearound, said unit including a web extending over the levers to limit upward movement thereof relative to the pin and including also a comb dependent from the web to space the levers, lugs extending from the top of the web overhanging part of said frame, and means passing through the lugs into the frame holding the unit in normal stationary position, said means being removable and when removed enabling the unit to swing around the pin to a position permitting upward removal of a lever from said pin.

20 5. In loom shedding mechanism having a pattern chain and a heel pin on which are pivoted vibrator levers which extend over the chain, a combined heel shell and comb unit mounted on the pin for angular movement therearound, said unit having a web normally extending over the levers to limit upward movement of the latter relative to the pin and having also a comb dependent from the web spacing the levers and holding the latter in register with the pattern chain, and a chain guard finger mounted on the unit out of vertical register with said levers, said unit when moving angularly around said pin

25 moving the web to one side of the levers to permit upward removal of a lever from the pin and moving said finger upwardly with said unit at one side of said levers.

30 6. In loom shedding mechanism having a heel pin and a plurality of vibrator levers pivoted thereon, a combined heel shell and comb unit having a web extending over the levers to limit upward movement of the latter relative to the pin and having a comb depending from the web to space the levers, bearings secured to and depending from the web receiving the pin to provide for pivotal movement of the unit around the pin, and clamp means associated with one of said bearings normally holding the unit stationary with respect to the pin, said clamp means being releasable to permit angular movement of the unit around the pin to move the web and comb to a position out of the path of a lever moving upwardly from the pin.

35 7. A combined heel shell and comb unit for a loom shedding mechanism having a heel pin on which vibrator levers are pivoted, said unit comprising a web for location over the levers, a flange depending from the web and slotted to provide a comb for the levers, and bearings secured to and depending from the web to receive the heel pin.

40 8. A combined heel shell and comb unit for a loom shedding mechanism having a heel pin on which vibrator levers are pivoted, said unit com-

prising a web to be located over the levers and having depending from one side thereof a flange slotted to serve as a comb to space the levers and having depending from the other side thereof a solid flange to reinforce the web, and bearing means secured to the web located between said flanges to receive the pin.

9. A combined heel shell and comb unit for a loom shedding mechanism having a pattern chain and a heel pin on which vibrator levers are pivoted, said unit comprising a web for location over the levers, a flange depending from the web having a part thereof slotted to form a comb to register the levers with the pattern chain, bearing means on the unit to receive the heel pin, and a chain guard finger mounted on said unit at one side of said slotted part of the flange.

10. A combined heel shell and comb unit for a loom shedding mechanism having a pattern

chain and a heel pin on which vibrator levers are pivoted, said unit comprising a web for location over the levers, a flange depending from the web having a part thereof slotted to form a comb to register the levers with the pattern chain, bearing means on the unit to receive the heel pin, and a chain guard finger mounted on said flange at one side of the slotted part thereof.
